PRESSURE MEDIUM CONDUIT

Ernst Möller, Karlshorst, Berlin, Germany, assignor to Knorr-Bremse Aktiengesellschaft, Berlin, Germany, a corporation of Germany

Application October 12, 1932, Serial No. 637,378
In Germany October 15, 1931

3 Claims. (Cl. 303—82)

The subject of this invention is an apparatus which serves to increase the velocity of a pressure-varying impulse in a pressure-medium conduit.

Such an apparatus has been proposed in which 5 special valve-like devices are connected to the pressure-medium conduit, which transmit the energy of an introduced pressure-varying impulse from one section of the conduit to another, with a velocity greater than that of sound in air.

10 In the application of this apparatus to a pressure-medium brake for railway vehicles, which has already been proposed, a valve apparatus is provided as close as possible to each end of the vehicle, and both are connected together for 15 example by a draw wire, which is attached directly to the piston of the accelerator valves, which act to release pressure medium from the conduit.

This arrangement does not yet appear to be 20 sufficiently complete. It is in the nature of the accelerator that the smaller the pressure impulse to which the accelerators respond can be kept, the greater is the velocity of transmission, as the 25 effective pressure impulses are not propagated through the couplings in an ideal perpendicular wave front, but with a temporarily rising one. In practice it is not possible to arrange the wires connecting the accelerators in the individual cars 30 so that the friction conditions are the same in all the cars. The result of this is that wagons with higher wire friction give a delayed response, and the total time of transmission is undesirably lengthened. An unnecessary delay can also occur 35 when, in the course of time, the wires have become harder to move due to rust formation or to dirt collecting on them. This would appear especially undesirable in cases where, in a train provided with accelerators of the type indicated 40 above, cars are included without such apparatus, as it is known that a wave front in air becomes more flattened the longer is its path.

The problem of the invention is to overcome 45 this defect. According to the invention this is done by completely withdrawing the piston, which determines the response of the accelerator, from the influence of the wire, so that it no longer comes into contact with the wire. The piston is 50 formed as an independent piston which is under the conduit pressure on one side and under the control chamber pressure on the other side, and commands a valve which controls the movement of a special piston connected with the draw wire.

The apparatus according to the invention is 55 shown schematically in the drawing in five constructional examples. Forms of construction

have been chosen as examples in which each piston of the pair of accelerators carried on a car is connected by a draw wire with the outlet device of the other accelerator, whereby this outlet device permits conduit air to flow, not directly 5 into the atmosphere but into a chamber.

In view of the fact that the two accelerators belonging to one car are counterparts and completely resemble one another constructively and are mounted at opposite ends of the vehicle in 10 the manner of mirror images, in the five figures of accelerators of various types of construction the left hand accelerator only (from the point of view of the observer) carried on the vehicle is shown.

The piston 4, acted on by compressed air from the brake pipe 1, has a hole 3 through which a control chamber 5 is filled to the pressure ruling in the main conduit. A piston 26 can be operated by compressed air from the control chamber 5 20 through a valve 25 controlled by the piston 4. The other side of the piston 26 is normally connected with the free air through a receiving chamber 11 and hole 12. The piston 26 is firmly connected through the draw wire 6 with the spring 25 loaded valve 9 of the right hand accelerator, not shown in the drawing, whose piston 26 in turn is firmly connected through the draw wire 6a with the spring loaded valve 9 of the left hand accelerator shown. When the second mentioned piston 26 is moved to the right this valve 9 allows compressed air from the main conduit to reach the receiving chamber 11.

It is desired to keep the dimensions of the receiving chamber as small as possible, so that the 35 brake accelerator may also be small. For this reason the subject of the invention as shown in Figure 1 is very much simplified by forming the guide tube 27 surrounding the wires 6 and 6a as a part of the receiving chamber, as shown in Figures 2 to 5. In this connection the guide tube 27 does not need to be particularly air tight; it may be so connected to the brake accelerator that the hole 12 in the receiving chamber can be omitted.

The method of operation of the apparatus is as 45 follows:—

If the pressure in the main conduit 1 is reduced, and the pressure-varying impulse coming from the left reaches the accelerator, the piston 4 of this latter is moved upwards by the pressure 50 in the control chamber 5, which cannot equalize itself quickly through the small hole 3 in the piston with the pressure in the main conduit 1, and the valve 25 is opened. The piston 26 is then actuated by compressed air from the control chamber 55

ber 5 and moves towards the left. By this movement the valve 9 of the second accelerator (not shown) which is firmly connected by the wire 6 with piston 26, is opened against the pressure of its loading spring; compressed air from the main conduit 1 reaches the receiving chamber 11 and causes a reduction of pressure at the other end of the car, which is at once transmitted to the accelerator of the next car. The left hand side 10 of the piston 26 is acted on by compressed air reaching the receiving chamber 11, and after a certain pressure has been reached this, in conjunction with the spring which loads the valve 9, causes the closing of this latter. By this means 15 no more compressed air is drawn off from the main conduit 1 than is necessary for the purpose. The compressed air from the receiving chamber 11 escapes slowly through the hole 12 into the atmosphere; as, when the compressed air from the 20 receiving chamber 5 is given up to the cylinder of the piston 26, the piston 4 is again moved downwards by the conduit pressure and closes the valve 25, the compressed air which is on the right hand side of the piston 26 reaches the left hand 25 side, either owing to the piston 26 not being an air tight fit or through a narrow nozzle, and from there also passes out into the atmosphere.

A particular advantage of this arrangement consists in that when the valve 25 is opened the 30 piston 26 receives the full pressure of the control chamber. A very definite pressure wave is thereby propagated through the wire, which manifests itself in high velocities of valve opening. The further result is obtained that the piston 26 need 35 only be very small and thereby the piston 4 which is directly influenced by the conduit pressure, and the control chamber 5 of this piston, can be substantially reduced in comparison with constructions already proposed.

Naturally, the piston 26 instead of being actuated by control chamber air, may be actuated by 40 compressed air from a special chamber (Figure 4) or from the main conduit (Figure 3). Further, the movement of the piston 26 can take place in 45 such a way that there is at first pressure acting on both its sides, which is reduced or removed on one side, with reduction of pressure, in the main conduit, by means of the valve 25 (Figure 5).

What I claim and desire to secure by Letters 50 Patent of the United States is:—

1. In connection with a pressure medium conduit and particularly a compressed air brake pipe extending the length of a railway car, a pair of valve housings connected to said brake pipe

and spaced apart so that one housing is disposed at each end of said car, a control piston movably disposed in one of said housings and having a draw wire secured thereto connecting said piston with an outlet valve in a valve housing fixedly associated with the other housing at the other end of the car, a second control piston movably disposed in said other housing also having a draw wire secured thereto and connecting said second piston to a second outlet valve in a valve 10 housing which is fixedly associated with the first one of said housings, means resiliently tending to close said outlet valves, each of which outlet valves when open, admits air from said brake pipe into a chamber provided with means for releasing 15 air therefrom at a predetermined rate of flow, a pressure medium storage chamber formed in each of said first pair of housings, a pair of additional valves individually disposed in said first pair of housings and interposed between 20 said control pistons and the storage chambers in said pair of housings so as to individually control transmission of air from said storage chambers to the control pistons, and a pressure responsive piston both interposed between the 25 storage chamber in each of said pair of housings and the supply thereto of pressure medium from said brake pipe and effective to open the one of said additional valves respectively associated with and controlling transmission of air from said 30 latter storage chamber in each case.

2. Brake control apparatus according to claim 1, wherein the pressure responsive piston in each of the pair of housings is provided with means which are effective to gradually transmit air pressure to the storage chamber associated with the piston in each case from the brake pipe while preventing any sudden flow of pressure medium from said storage chamber toward said brake 40 pipe.

3. Brake control apparatus according to claim 1, wherein the pressure responsive piston in each of the pair of housings is provided with means which are effective to gradually transmit air pressure to the storage chamber associated with the 45 piston in each case from the brake pipe while preventing any sudden flow of pressure medium from said storage chamber toward said brake pipe, while the control pistons are constructed to allow air to escape from between the same and the 50 additional valves when the latter individually close and the outlet valves controlled by said pistons in either case tend to close.

ERNST MÖLLER.
